UNITED STATES PATENT OFFICE.

JULIUS M. GERMANSON, OF MILWAUKEE, WISCONSIN.

TILTING-CHAIR IRON.

SPECIFICATION forming part of Letters Patent No. 729,571, dated June 2, 1903.

Application filed April 5, 1902. Serial No. 101,530. (No model.)

To all whom it may concern:

Be it known that I, JULIUS M. GERMANSON, residing at Milwaukee, in the county of Milwaukee and State of Wisconsin, have invented 5 a new and useful Improvement in Tilting-Chair Irons, of which the following is a description, reference being had to the accompanying drawings, which are a part of this specification.

10 My invention has relation to improvements in tilting-chair irons.

In a common form of tilting-chair iron the head or socket piece of the chair-iron spindle is provided with upwardly-extending arms, 15 and the spider-frame is provided with depending arms extending alongside of the head-piece arms, the said sets of arms being connected by a transverse shaft, on which the spider-frame is adapted to tilt. This construction necessarily involves considerable 20 machine-work, inasmuch as holes are required to be drilled in the arms referred to for the passage of the shaft therethrough.

It is the primary object of my invention to 25 provide a construction wherein all machine-work is avoided and all the parts can be cast and when taken from the sand are in condition to be adjusted together without the necessity of drilling holes or the employment of 30 a separate shaft, thereby promoting simplicity and saving in expense in manufacture and also simplifying the adjustment of the parts together or their separation when necessary.

With the above primary object and other 35 incidental objects in view the invention consists of the devices and parts or their equivalents, as hereinafter set forth.

In the accompanying drawings, Figure 1 is 40 a side elevation of my improved tilting-chair iron. Fig. 2 is a plan view thereof. Fig. 3 is a section on the line 3-3 of Fig. 1, and Fig. 4 is a fragmentary detail view illustrating the tilting washer.

Referring to the drawings, the numeral 5 45 indicates the spider-frame, which is provided with the usual arms 6, which extend in a horizontal plane and are secured at their ends to the under side of the chair-seat. The spider is also formed with the depending medial side 50 arms 7.

The numeral 8 indicates the head-piece, provided with the usual socket for the upper

end of the chair-iron spindle. (Not shown.) This head-piece is provided near opposite ends with upwardly-extending arms 9, which 55 extend adjacent to the inner sides of the arms 7 of the spider-frame. At opposite ends the head-piece is provided with upwardly-extending lugs 10, recesses 11 being formed between the same and the arms 9. These 60 spaces are intersected by integral pivot-pins 12. The lower ends of the arms 7 are recessed and the furcate parts formed by these recesses straddle the pins 12, said pins thereby forming pivots upon which the spider-frame can tilt. The upper ends of the arms 9 extend into openings 13, formed at opposite ends of the transverse connecting-piece 14 of the spider-frame. One side bordering edge of each of these openings is provided with a horizontal ledge or flange 15, and each flange is provided at a medial point of its edge with a recess 16. At the upper end of each arm 9 is provided a laterally-extending lip 17, the upper end of each of said 70 arms extending a sufficient distance upwardly into the opening 13 to permit the lug to extend over the flange 15. The head-piece 8 is further provided intermediate of its ends with an upwardly-extending lug 18, said lug 80 provided at its upper end with an opening 19, through which the threaded end of a rod 20 passes, the threaded extremity thereof having turned thereon the interiorly-threaded tubular extension 21 from a hand-wheel 22. 85 The opposite end of the rod 20 passes through a cross-bar 23 and is provided with a head bearing against the outer side of the cross-bar. The said cross-bar on its inner side and at opposite ends is provided with inwardly-extending lugs 24, which project into the outer ends of coiled springs 25, the inner 90 ends of said springs surrounding lugs 26, 26 projecting from the transverse connecting-piece 14 of the spider-frame. By turning the hand-wheel 22 the tension of the springs 25 may be regulated, as is common in this class of devices. I prefer to employ in connection with this part of the device a rocking washer 27, which surrounds the rod 20 and is interposed between the end of the tubular extension 21 of the hand-wheel and the lug 18, the said lug 18, provided with projecting rounded ears 28, which bear against one side 100.

of the washer. By this construction when the spider is tilted a slight rocking play to the springs 25 is permitted, whereby the stress under which said springs are brought 5 on account of said tilting operation is always maintained in line with the center of the rod 20.

From the foregoing description it will be seen that the spider-frame and the head-piece 10 may be each formed from a single casting, and when taken from the sand they are ready to be fitted together without the necessity of drilling holes therein or of adjusting or securing additional parts thereto, such as a 15 pivot-shaft. My improvements, therefore, not only greatly simplify the construction, but also reduce the expense of manufacture, and, furthermore, provide for the parts being shipped separately, and subsequently readily 20 adjusted together when received by the person to whom shipped. The parts can also be readily detached or separated when necessary. Normally the lips 17 of the arms 9 extend 25 over the solid portions of the flanges 15 or are out of register with the recesses 16, and in the tilting of the chair-seat and spider-frame connected thereto the said lips work over the said flanges, which flanges are preferably on a slight arc of a circle in order to 30 permit free tilting movement. When it is desired to separate the parts, all that is necessary to be done is to bring the lips 17 and recesses 16 into registration, when of course the spider-frame can be readily lifted upwardly 35 and separated from the head-piece. On the other hand, in putting the parts together the lips 17 and recesses 16 are brought into registration and the parts adjusted together, so that said lips will be brought above the 40 flanges 15, and the sockets in the lower ends of the arms 7 will be engaged by the pivot-pins 12.

What I claim as my invention is—

1. In a chair-iron spider, in combination 45 with a head-piece having horizontal supporting members, of a spider-frame mounted pivotally and removably on the horizontal supporting members, means for normally holding the head-piece and spider-frame together 50 but permitting of the turning of the spider-frame on the supporting members, and means, when the spider-frame and head-piece are in a certain position relatively to each other, for permitting of the removal of the spider-frame 55 from the supporting members.

2. In a chair-iron spider, the combination 60 with a spider-frame having flanges at opposite sides, and each flange having a recess extending inwardly from the edge thereof, and 65 said spider-frame also provided with depending arms, of a head-piece to which the depending arms of the spider-frame are removably pivoted, said head-piece provided with upwardly-extending arms having projecting 70 lips adapted to extend over the horizontal flanges of the spider-frame.

3. In a chair-iron spider, the combination

with a spider-frame having openings at opposite sides, and one side of the bordering edge of each opening provided with a projecting 75 flange recessed at one point, and said spider-frame also provided with depending arms, of a head-piece to which the arms of the spider-frame are removably pivoted, said head-piece provided with upwardly-extending arms, the 80 upper ends thereof extending into the openings, and provided with projecting lips extending over the flanges.

4. In a chair-iron spider, the combination 85 with a spider-frame having flanges at opposite sides, each flange having a recess extending inwardly from the edge thereof, and said spider-frame also provided with depending arms, said arms having open-ended recesses at their lower ends, of a head-piece having 90 pivot projections which the lower recessed ends of the depending arms of the spider-frame removably and pivotally engage, and said head-piece also provided with upwardly-extending arms, the upper ends thereof provided with projecting lips extending over the flanges.

5. In a chair-iron spider, the combination 95 with a spider-frame having flanges at opposite sides, each flange having a recess extending inwardly from the edge thereof, and said spider-frame also provided with depending arms, said arms having open-ended recesses at their lower ends, of a head-piece having 100 pivot-pins projecting laterally from opposite ends thereof, and which pins the lower recessed ends of the depending arms of the spider-frame removably and pivotally engage, and said head-piece also provided with upwardly-extending arms, the upper ends thereof provided with projecting lips extending over the flanges.

6. In a chair-iron spider, the combination 110 with a spider-frame provided with depending arms having recessed lower ends, of a head-piece having recesses at opposite ends, said recesses opening upwardly, and said recesses intersected by transverse pins, each pin receiving the recessed lower ends of the depending arms of the spider-frame.

7. In a chair-iron spider, the combination 115 with a spider-frame having flanges at opposite sides, each flange having a recess extending inwardly from the edge thereof, and said spider-frame also provided with depending 120 arms having their lower ends recessed, of a head-piece provided with its ends with upwardly-extending lugs, and near its ends with upwardly-extending arms, the spaces formed between the lugs and the arms being intersected by transverse pivot-pins which receive the lower recessed ends of the depending arms of the spider-frame, and the upwardly-extending arms of the head-piece provided at 125 their upper ends with projecting lips which 130 extend over the horizontal flanges.

8. In a chair-iron spider, the combination 135 with a spider-frame having flanges at opposite sides, each flange having a recess extend-

ing inwardly from the edge thereof, the said spider-frame also provided with depending arms, the said spider-frame and its parts being integral, of a head-piece to which the de-

5 pending arms of the spider-frame are removably pivoted, the said head-piece provided with upwardly-extending arms having projecting lips extending over the horizontal

flanges of the spider-frame, and said head-piece and its parts being also cast integrally. 10

In testimony whereof I affix my signature in presence of two witnesses.

JULIUS M. GERMANSON.
